ADDING-MACHINE.

1,226,064.

Specification of Letters Patent.

Patented May 15, 1917.

Application filed May 18, 1912. Serial No. 698,088.

To all whom it may concern:

Be it known that I, GEORGE CORDTS, citizen of Germany, residing at New York, county and State of New York, have invented new and useful Improvements in Adding-Machines, of which the following is a specification.

This invention relates to adding machines and has in view the production of a machine that is cheap, simple, compact, easy to construct, manipulate and repair and which is not liable to get out of order, all as will be explained in the following description and claims and the drawing, in 15 which—

Figure 1 is a top view, partly in section of the machine with the cover removed,

Fig. 2 is a section partly in elevation on the line 2—2 of Fig. 1,

Fig. 3 is a top view of the machine,

Fig. 4 is a side elevation of one side of a digit wheel,

Fig. 5 is a side elevation of the other side of the digit wheel,

Fig. 6 is a transverse vertical section of a digit wheel,

Fig. 7 is an elevation of the rack and pinion used to set the propelling wheel opposite any digit wheel,

Fig. 8 is an elevation of the segment and lever used in advancing a digit wheel any desired number of digits, and

Fig. 9 is a plan view of a disk placed adjacent to a digit wheel.

Referring to the drawing there is shown a container or casing 10, which for convenience may be separable into two or more parts. On the casing 10 are supported two shafts 11 and 12, the former carrying the 40 digit or adding wheels 13, and the latter carrying a propelling wheel 29, which moves the digit wheels when the operation of addition is carried on. The digit wheels are in the form of toothed wheels having the 45 successive digits 1 to 9 and 0 on the apex of the teeth as shown in Figs. 1 and 6. On the left side of each of the digit wheels is placed a disk 15, which has a circular portion 16 and a flat portion 16' at its periphery, and a projection 17 fitting in a corresponding groove 22 in the shaft 11 so that it will rotate with the shaft.

A pawl 18 pivotally carried on the side of

each digit wheel rests on the perimeter of the disk 15 and is caused to yieldingly engage therewith by a spring 19. When the pawl moves on the edge of the circular portion 16 of the disk it clears the teeth 21 of a ratchet wheel 20 on the right side of an adjacent digit wheel, and as the pawl passes over the flat portion 16' of the disk it is lowered sufficiently and caused by the spring to engage the ratchet teeth 21 of the wheel 20 moving said adjacent wheel with the connected digit wheel one step.

Fixed in the frame 10 is a stud shaft 32, on which is rotatably mounted a segment 23 having teeth 31 meshing with the teeth 26 of a wheel 25, which is fixed to a disk 24, both revolubly mounted on the shaft 12. 70 Fixed to the shaft 12 is a ratchet wheel 27 having ten teeth 28. A pawl 35 pivotally carried by the disk 34 is caused to engage with the teeth of the ratchet wheel 37 by a spring 36. Mounted on the shaft 18 to 75 have axial adjustment thereon and rotate therewith is a wheel 29. This wheel has teeth 30 adapted to mesh with the teeth of either of the digit wheels 13 and impart movement to the latter when the shaft 12 is 80 rotated in anti-clockwise direction. The segment 23 is moved forward and backward by a lever 24. As it is moved forward it will rotate the pinion 25 and connected pawl carrying disk 34 the pawl 35 riding over 85 the teeth of the ratchet wheel 27 and as the lever is returned to initial position the pinion 25 will be rotated in a reverse direction and the pawl 35 will engage with the teeth in the ratchet wheel 27 rotating 90 the shaft 12 and thereby the propelling wheel 29. The wheel 29 is adjusted on the shaft 12 by a rack 37 connected at one end to a plate 40 which is mounted on the hub 41 of the wheel 29 and held in place by a plate 42, the rack being actuated by a pinion 38 meshing with the rack, said pinion being fixed to a shaft which is rotated by a milled head 39 fixed thereto.

The digit wheels 13 are frictionally held 100 in adjusted position by the springs 43 pressing against pins 33 extending laterally from the teeth of the wheels. To the right of the digit wheels 13 is a disk 44 having an indentation 45 into which fits the top of a 105 spring 46 which presses against it and gives

to the digit wheels a definite and accurate zero position when the hub of the spring 46 engages in the indentation 45.

On the top of the casing there is a slot 47 through which are visible the various numerals or digits on the apex of the teeth of the wheels 13 as they are revolved. There is also a slot 48 in the casing in which moves an index or projection 50 extending from 10 the plate 40 connected to the propelling wheel which indicates opposite which digit wheel the propelling wheel 29 is placed, a row of numerals 49 adjacent to the slot being provided for the purpose.

15 The lever 24 moves in a slot 51 in the casing, a series of numerals 52 indicating the extent to which the lever should be moved to rotate the propelling wheel a pre-determined number of tooth spaces. In order to 20 return the adding wheels to zero position the shaft 11 is rotated by a milled head 53, a pawl pivotally carried by each digit wheel falling into the slot or groove 22 in the shaft and thereby coupling said wheels to 25 the shaft.

The operation of the machine is as follows: The propelling wheel 29 is first brought opposite the desired digit wheel 13. If units are desired it is adjusted so that 30 the teeth of such wheel will be in connection with the teeth of the first digit wheel; if tens are desired it is adjusted to coöperate with the second digit wheel, etc. After the propelling wheel has been properly adjusted 35 the lever 24 is pulled forward until it is opposite the digit or numeral on the scale 52 corresponding to the number to be added, and is then returned to initial position. Simultaneously with the forward movement 40 of the lever the pinion 25 and connected pawl carrying disk 34 is rotated causing pawl 35 to ride over the teeth of the ratchet wheel 27, and upon the return movement 45 of the lever the pinion 25 and disk 34 are rotated in opposite direction causing the pawl to engage with the ratchet wheel 27 and operatively connecting the propelling wheel to the pinion 25, and is turned the requisite number of steps or tooth spaces 50 and through it the corresponding digit wheel, and the number opposite which the lever 24 is placed is added and indicated by the digit wheels through the slot 47. Units, tens, hundreds and all other denominations 55 are added in the same manner. When the figure added produces a sum above ten the pawl 18 acts on the ratchet wheel of an adjacent number wheel moving it forward one step whereby in each case addition of figures of any denomination is carried on beyond the nine digits of each digit wheel.

In the setting of the numerals at zero the milled head 53 is rotated thereby rotating the shaft 11, the various pawls 54 drop into 60 the slot 22 in the shaft whereby the wheels

are coupled thereto, the head 53 being rotated until all of the digit wheels assume the zero position which will be indicated through the slot 47 when a new adding operation may be repeated.

What I claim as new is:

1. In an adding machine the combination of a shaft; a plurality of toothed wheels having digits on the apex of the teeth mounted on said shaft in juxtaposed relation; a toothed propelling wheel rotatable and adjustable on an axis parallel with the axis of the digit wheels to advance the digit wheels in one direction; means carried by the digit wheels coöperating when a digit wheel has made a complete revolution to advance the next adjacent digit wheel of higher denomination one tooth space, comprising a pawl carried upon the side of each digit wheel, a disk having a flat portion fixed on the shaft adjacent each of the digit wheels and with the perimeter of which disks the pawls engage, and a ratchet wheel connected to the side of the wheel of the next higher denomination with which the pawls coöperate as they pass over the flat portions of the disks; means to manually rotate the digit wheel shaft; and a pawl carried by each of the digit wheels to coöperate with a longitudinally extending groove in the shaft to return all of the digit wheels to initial position.

2. An adding machine, comprising in combination a casing, a plurality of juxtaposed toothed wheels having digits on the apex of the teeth mounted in the casing to have independent movement in one direction; an opening in the casing with which axially aligned digits on the digit wheels are adapted to register; means carried by said wheels and operable when the wheels have made a complete revolution in one direction to advance the next adjacent wheel of higher denomination one tooth space; a shaft extending parallel with the axis of the said digit wheels; a toothed wheel mounted on said shaft to have adjustment along the same and rotatable therewith and adapted to mesh with either of the digit wheels; means carried by said wheel to extend through an opening in the casing and register with numerals on the casing to indicate the position of said wheel with relation to the digit wheels; manually operable means to adjust such wheel along its shaft; and a lever to impart movement to the shaft and connected wheel, substantially as and for the purpose specified.

3. An adding machine comprising in combination a casing; a shaft journaled in said casing; a plurality of juxtaposed toothed wheels having digits on the apex of the teeth loose on said shaft and have independent movement on the shaft; an opening in the casing through which an axially aligned

- row of digits of the digit wheels are adapted to be exposed; a toothed propelling wheel adjustable along an axis parallel with the axis of the digit wheels and adapted to 5 mesh with either one of the latter wheels to advance said wheels in one direction, said wheel having means to project through an opening in the casing to indicate the position of said wheel; means to rotate said 10 wheel a predetermined distance, means carried by the digit wheels to coöperate when a digit wheel has been actuated by the propelling wheel and made a complete revolution to advance the adjacent digit wheel of 15 the next higher denomination one tooth space; means connected to the digit wheel shaft to manually rotate the same; and pawls carried by the digit wheels to engage in a longitudinal groove in the shaft when 20 the digit wheel shaft is rotated in a direction reverse to the movement of the digit wheels imparted thereto by the propelling wheel to return the digit wheels to zero position.
4. An adding machine comprising in combination a casing; a shaft journaled in said casing; a plurality of juxtaposed toothed wheels having digits on the apex of the teeth loose on said shaft; an opening in the casing through which an axially alined row of 25 digits on said wheels are adapted to be exposed; a shaft in the casing extending parallel with the axis of the digit wheels; a toothed propelling wheel slidably mounted on said shaft and to rotate therewith; means to adjust said wheel along its shaft to cause 30 it to mesh with either one of the digit wheels; means connected to said propelling wheel projecting through an opening in the casing to indicate the position of said wheel; means carried by the digit wheels to co- 35 operate when a complete revolution has been imparted to a digit wheel in one direction to advance the adjacent digit wheel of the next higher denomination one tooth space; and means to rotate the propelling shaft, comprising a toothed segment having a lever, a pinion with which said segment meshes loose on the shaft of the propelling wheel, a pawl carried by said pinion, and a ratchet wheel 40 fixed on the shaft of the propelling wheel 45 with which the pawl coöperates when the segment is moved in one direction to couple the pinion to the shaft, substantially as and for the purpose specified.
5. In testimony whereof, I have signed my name to this specification in the presence of two subscribing witnesses, this 15th day of May 1912.
